UNITED STATES PATENT OFFICE.

NELS J. ROTHSTEN, OF BELOIT, WISCONSIN.

FLY-WHEEL.

1,103,843.

Specification of Letters Patent.

Patented July 14, 1914.

Application filed May 19, 1913. Serial No. 768,598.

To all whom it may concern:

Be it known that I, NELS J. ROTHSTEN, a citizen of the United States, residing at Beloit, in the county of Rock and State of Wisconsin, have invented certain new and useful Improvements in Fly-Wheels, of which the following is a specification, reference being had therein to the accompanying drawing.

10 This invention relates to fly wheels and has for its object the production of an efficient fly wheel for regulating the speed of an engine, while taking off or putting on a load, therefore producing an even rotation.

Another object of this invention is the production of an efficient interlocking means formed in the hub of the wheel, whereby the spokes may be automatically swung for 20 overcoming the uneven impulses of an engine.

With these and other objects in view, this invention consists of certain novel constructions, combinations and arrangements of 25 parts as will be hereinafter fully described and claimed.

In the drawings: Figure 1 is a side elevation of the fly wheel. Fig. 2 is an enlarged vertical section through the hub of the 30 wheel. Fig. 3 is a section taken on line 3—3 of Fig. 1. Fig. 4 is a top plan view of the hub-portion of the wheel. Fig. 5 is a section taken on line 5—5 of Fig. 2. Fig. 6 is a detail perspective of one of the rim-sections 35 of the fly wheel. Fig. 7 is a detail perspective of one of the interlocking blocks carried by the hub of the wheel. Fig. 8 is a sectional view through the joint of two of the interlocking blocks, showing the outer shoulders of the same in a locked engagement. Fig. 9 is a section through the joint of two 40 of the interlocking blocks, showing the inner shoulders thereof in locked engagement.

By referring to the drawing by numerals 45 it will be seen that 1 designates the hub of the wheel, which is provided with a channel 2 around the periphery thereof. A plurality of interlocking blocks 3 are pivotally mounted in the channel 2 by means of the supporting pins 4, as is clearly illustrated in Figs. 2 and 3 of the drawings.

Each of the interlocking blocks 3, is provided upon one end with a knob-portion 5, which is substantially semi-circular in shape 55 and at the other end, with a substantially semi-circular socket 6. The knob of one

block 3 is adapted to interlock with the socket of the adjacent block, thereby connecting all of the blocks in an endless chain.

A spoke or arm 7 is carried by each of the 60 blocks 3, and are securely held in engagement therewith by means of the pivot pins 4. The outer ends of the spokes or arms 7 carry segmental rim-sections 8, which are secured to the spokes 7 by means of pins 9 65 which securely hold the spokes in the apertures 10 formed in the rim-sections, as illustrated in Figs. 3 and 6.

As illustrated in Fig. 2, the knobs 5 fit loosely in the sockets 6 for allowing the 70 arms or spokes to freely swing upon the hub 1. The swing of the blocks 3 and arms 7, will be limited however, for the shoulders 11, formed near the outer face of the blocks 3 adjacent the knobs 5, by engaging the 75 shoulders 12 formed adjacent the sockets 6, will limit the swing in one direction and the lower faces of the blocks 3 will limit the swing in the opposite direction, when the same are brought into contact with each 80 other.

From the foregoing description, it will be seen that if the fly wheel should be rotated with sudden impulse, the arms 7 by being loosely mounted within the hub will freely 85 swing, thereby causing the rim-sections of each pair of arms to be drawn together thereby equalizing the rotation of the wheel and overcoming the uneven impulses of the engine. For the purpose of illustration, attention is invited to Fig. 2 and by carefully considering the arrows placed thereon, the relative swing of the blocks 3 will be obvious.

What is claimed is:—

1. A fly wheel of the class described comprising a hub, a plurality of blocks pivotally mounted upon said hub, each block provided with a spoke receiving socket, a spoke carried by each block, a section of a rim carried by each spoke and constituting a balancing weight therefor, each block provided with a projecting knob at one end and a receiving socket at the other end, the socket of each block being slightly deeper than the 100 knob of the adjacent block adapted to fit therein for allowing the free swinging movement of said blocks and reducing the friction or engagement between said blocks, said blocks adapted to simultaneously swing 105 under a sudden impulse or rotation for equalizing the rotation of said hub.

2. A device of the class described comprising a hub, blocks pivotally carried thereby, each block provided with a socket at one end, a rounded knob carried by each block, the knob of one block adapted to fit in the socket of the adjacent block, a spoke carried by each block, and a weight carried by each spoke adjacent the outer end thereof, said blocks provided with stop shoulders formed adjacent said sockets and knobs for limiting the swing of said blocks upon

said hub, the swing of one block adapted to control the swing of the adjacent blocks for causing the center of gravity of the weight of said spoke to be shifted under a sudden swing of said wheel. 15

In testimony whereof I hereunto affix my signature in presence of two witnesses.

NELS J. ROTHSTEN.
